United States Patent Office.

ANTHONY ISKE, OF LANCASTER, PENNSYLVANIA.

Design No. 2,676, dated June 18, 1867.

DESIGN FOR A COMBINED HAMMER, TACK-DRAWER, WRENCH, &c.

The Schedule referred to in these Letters Patent and making part of the same.

TO ALL WHOM IT MAY CONCERN:

Be it known that I, ANTHONY ISKE, of Lancaster, in the State of Pennsylvania, have originated a new Design or a new Pattern in a Casting, embracing a Hammer, Tack-Drawer, several sized Wrenches, Hooks, and Curves adapted to lifting pot-lids, dishes, griddles, and the like, being neat and ornamental, and highly desirable in every household, of which the accompanying drawing, making part of this specification, gives a full, clear, and exact description of its configuration and combination, being cast of malleable or common metal, with the curves, hammer, and open space of the form and figure shown.

What I claim as my invention, and desire to secure by Letters Patent, is—

The design and configuration of the household implement herein shown and set forth.

Witnesses:

CHAS. R. FRAILEY,
JACOB STAUFFER.

ANTHONY ISKE.
